UNITED STATES PATENT OFFICE.

CALVIN RUSSELL, OF PENN YAN, NEW YORK, ASSIGNOR TO CARRIE H. RUSSELL, OF PENN YAN, NEW YORK.

METHOD OF MAKING A PLURALITY OF SHINGLES FROM A SINGLE SHEET OF MATERIAL.

1,274,605.

Specification of Letters Patent. Patented Aug. 6, 1918.

Application filed January 3, 1914. Serial No. 810,176.

To all whom it may concern:

Be it known that I, CALVIN RUSSELL, a citizen of the United States, and resident of Penn Yan, county of Yates, and State 5 of New York, have invented an Improvement in Methods of Making a Plurality of Shingles from a Single Sheet of Material, of which the following is a specification.

My invention has for its object an improved method of rapidly and cheaply manufacturing shingles of special shapes, more particularly from paper or wool felt material impregnated with asphaltum or other suitable hydro-carbon; and more especially to sub-divide a sheet of the material from which the shingles are to be cut so that there shall be a minimum waste, while maintaining the proper and necessary proportions of the shingle structure, to enable 15 it to be properly assembled with similar shingles to provide a roofing structure.

More specifically stated, my invention comprehends sub-dividing the sheet of material from which the shingles are to be made, by one or more zig-zag or symmetrical reversing cuts arranged in the direction of one of the dimensions of the sheet, and connecting cuts meeting the points or narrow portions of the zig-zag cuts and arranged in the direction of the other dimension of the sheet, whereby in the preferred form of shingle cut from such sheet there will be parallel sides and the body pointed or narrowed at one or both ends according 30 to the design desired. In those cases where the shingles are to be cut to present rectangular lower parts when arranged on the roof, there will only be the upper ends pointed, while, on the other hand, in those 35 cases where the shingles are to present pointed or diamond-shaped lower portions when arranged upon the roof, either the lower part alone or both ends of the shingle are pointed, but in the latter case this pointing is preferably different where great economy is desired, that is to say, the lower end has a point of approximately ninety degrees, whereas the upper end may have a point approximating sixty degrees, more or less. My invention, therefor, comprehends broadly the sub-dividing of a sheet of flexible material of which the shingles are to be made, by a combination of zig-zag or reverse cuts and straight cuts which may be 55 simultaneously made, or made in succession,

the difference in shingle structure produced being solely as to the special form of the dies which may be employed in the actual manufacture.

The particular feature upon which the 60 novelty of the special cutting depends resides in the cutting of the sheet in such manner that the points or narrow portions of the shingles are formed by sub-dividing the body of the sheet in a way so that the material which forms a point or narrow portion on one shingle is that portion of the sheet which is interposed between two parts of the sheet which form points or narrow portions of adjacent shingles upon each side 65 of the point or narrow portion of the first mentioned shingle; the shingles so produced having a total length equal to that required for properly overlapping similar shingles in a roof structure, and the saving of material over the construction of a rectangular shingle being equal to a strip of the body material of a width equal to the pointed or narrow end or ends of a shingle according 70 to the special angularity or shape employed, 75 and whether the shingle is pointed or narrow at one end only or at both ends.

My improved method of forming the shingles from a sheet of material will be better understood by reference to the accompanying drawings, in which:—

Figure 1 is a plan view of a sheet in which the line of cutting is indicated for making a shingle pointed at one end only; Fig. 2 is a similar plan view but illustrating the 80 method of cutting where both single and double pointed shingles are to be made; Fig. 3 illustrates a plan view of a sheet so cut as to provide shingles in which both ends are pointed, and Figs. 4 and 5 are similar views 85 illustrating a modified form of cutting in which shingles are produced pointed at one or both ends.

These figures illustrate the general manner of cutting the sheets under the method 100 of my invention and are by way of example only, the narrowed end or ends of the shingle being formed by straight lines meeting at an angle, said manner of forming the ends being simpler and cheaper in respect 105 to the dies necessary than where the reversing cuts provide the shingle with narrow end portion or portions of other shapes.

First referring to the cutting illustrated in Fig. 1, we have the rectangular body or 110

sheet 2 divided throughout its length by a zig-zag cut 3 and the two serrated parts so formed further sub-divided respectively by the parallel, transverse and staggered arrangement of cuts 4 and 5. The cuts 4 extend from one series of the points of the zig-zag cuts to the side of the sheet, whereas the cuts 5 extend from the other series of the points of the zig-zag cutting to the other side of the sheet. In this way shingles are produced of the right width and total length, made rectangular at one end and pointed at the other. It will also be seen that with every set of these shingles so formed there will be two half shingles, and this is desirable because it necessarily follows in arranging the shingles upon the roof that alternate rows will have to terminate with half shingles. It will be further observed that there is a saving in material equal to the total length of the sheet and of a width equal to the distance between parallel lines through the two series of the points. In actual practice this saving of material varies from 20 to 30 per cent. of the total material required for rectangular shingles where the shingle is approximately eight inches wide and ten inches long. The proportion of these shingles is such that they overlap and engage each other in the actual roof so that the ultimate roof structure with shingles of the character here described is just as waterproof and solid as if the rectangular shingles themselves were employed. One form of roof structure adapted to be made from shingles of this character is shown in Letters Patent No. 1,070,738, granted to me on August 19, 1913. This great saving in shingle material required for properly covering a roof is due to the special manner in which a plurality of these shingles or shingle structures are cut from a single sheet, and which forms a special method of this application.

Referring now to Fig. 2, I have shown a somewhat more extended manner of cutting the shingles by combined zig-zag and parallel transverse cuts, whereby there are three series of shingles formed instead of two series as indicated in Fig. 1; and in this case, moreover, there are three forms or shapes of shingles produced, namely those indicated at A, B and C. The cuts 3 and 4 in this figure approximate the cuts 3 and 4 of Fig. 1 and produce the shingles A, similar to those in Fig. 1. The zig-zag cuts 6, which are in general parallel alignment to the zig-zag cuts 3, but with the points arranged in the reverse order, provide the pointed ends of the other shingles B and C. The double pointed shingles B are separated by the parallel cuts 5^a, which correspond to the cuts 5 of Fig. 1, but instead of terminating in the side of the sheet, they terminate in the points of the zig-zag cuts 6.

In this manner the middle row of shingles B may be formed with points at opposite ends of different angularity, that is to say, the points formed by the zig-zag cuts 3 may approximate ninety degrees, while the points formed by the zig-zag cut 6 may approximate sixty degrees. These angularities or shapes of the pointed or narrow end portions may be varied, if so desired. The remaining parallel cut 7 between the other series of points and zig-zag cuts 6 extend to the edge of the sheet, so that we have by this cutting the shingles C which correspond to the shingles A, but the pointed parts are sharper or approximately of sixty degrees instead of ninety degrees as in the shingles A. Moreover, for the shingles of a given length the length of the cuts 7 of the shingles C will be less than the cuts 4 of the shingles A. The shingles A may be employed with either end up in the actual roof structure, according to whether the lower edges of the shingles are to be straight or pointed, whereas the shingles B and C are both intended to have their more pointed ends upward when arranged in the roof structure, the former providing diamond pointed effect to the exposed portions of the shingles, while the latter produce the straight edge or rectangular effect to the exposed portions of the shingles. It is evident that the angularity of the points of the zig-zag cutting 3 of Fig. 1 may correspond to the angularity of the points of the zig-zag cut 6 of Fig. 2 or of any other angularity or narrowing shape which it is desirable to employ in practice.

Referring now to the cutting shown in Fig. 3, I have arranged the zig-zag cuts and straight cuts corresponding to what is shown in 3, 5^a and 6 for the shingles B of Fig. 2, but arranged so that all the shingles have points at opposite ends, and in which the points at one end are more pointed than at the other end. In the cutting of this arrangement of the zig-zag and parallel cuts I also provide half shingles, but for reasons already stated the production of the half shingles is not objectionable as they are necessary in the arrangement of the shingles upon the roof. In the cutting of this arrangement of zig-zag and parallel cuts of Fig. 3, the length of the shingles may run in the direction of the length or transversely of the sheet as desired, and in this particular case the width of the sheet should be relatively great if the shingles are to run in the direction of the length of the sheet so as not to produce an excessive number of half shingles.

Referring now to the construction shown in Fig. 4, we have zig-zag cuts 3 arranged transversely of the sheet, and parallel cuts 4 and 5 longitudinally of the sheet, and the said parallel cuts again severed (if desired)

transversely by transverse straight cuts 8 intermediate of two successive zig-zag cuts 3 and 3^a. These zig-zag cuts 3^a are indicated as having their points in the reverse order of the points of the zig-zag cut 3 as in the case of Figs. 2 and 5 to form double pointed shingles when the straight cuts 8 are omitted.

In all of the cutting there is a percentage 10 of saving of material over the material required in rectangular shingles as ordinarily employed, whether said shingles be trimmed for diamond pointed design or not, as said material when removed in pointing my 15 proved shingles is used to form a portion of other shingles. As before pointed out, there was a saving of twenty to thirty per cent. in 20 surface material required for covering a roof with shingles when cut with points or narrowed portions at one end by the zig-zag and parallel cutting of Fig. 1, and this is increased in the particular cutting of Fig. 3, as in this case there may be a saving of 25 proximity forty-five per cent. with a shingle ten inches long, and eight inches wide, maximum dimensions.

It is also to be kept in mind that if the cutting shown in Fig. 1 has the zig-zag cuts 3 in the direction of the length of the sheet, 30 there will be approximately no half shingles made, or at least only one or two to each sheet, but if the zig-zag cut is arranged transversely to the length of the sheet, then by having a sheet of great width, there will 35 be one half shingle to every transverse row of full shingles. When this form of cutting is employed, it may be considered as illustrated in Fig. 4. The same general statement may be made in respect to the half 40 shingles in the arrangement of cutting shown in Fig. 2, but such half shingles will only be produced at the ends.

It is immaterial to my invention what 45 particular construction of machine may be employed for producing the zig-zag and parallel cuts, as such may be made by dies on a stamping press, or upon a cylindrical cutting machine, as my invention is not restricted to any particular character of machine or means for producing the cuts or the 50 angles of the points of the cuts, and I therefore do not restrict myself in this respect.

The material from which these shingles are preferably made is a wool felt material 55 of uniform thickness impregnated with asphaltum to give a soft and pliable body and provide sufficient hydrocarbon to exude to bind the shingles together when upon the roof and subjected to the sun's rays, and 60 with the surface covered with a vitreous material which may be of broken stone, slate or crushed brick for example, but I do not restrict myself to this particular character of material, as the material may 65 be of felt paper or cardboard impregnated

with any suitable material to make it impervious; and shingles may be employed with or without the vitreous coating. In fact, any suitable sheeting having body sufficient to form shingles and capable of 70 being severed by cutters may be employed for the purposes of my invention, but the material should be pliable or of tenacity which will permit cutting without cracking.

I have used the words "zig-zag cuts" in 75 a generic sense, meaning "symmetrical reverse cuts," and while I have preferred that the cuts shall be formed by straight cuts meeting at an angle to form angular or sharp points, it is to be understood that 80 any reverse cutting may be employed so long as I obtain the narrow or relatively pointed ends such as would, by one cut, provide the narrow or pointed ends of two sets of shingles without waste of material and 85 I therefore do not limit myself to any particular form of the points or narrow end portions.

In this application no claim is made to 90 the shingle structures as articles of manufacture, as they will form subject matter of other applications, this case being restricted to the method of procedure in the manufacture of such shingles.

Having thus described my invention, what 95 I claim and desire to secure by Letters Patent is:—

1. The herein described method of forming a plurality of shingle structures from a single sheet of material, which consists in 100 severing the sheet in the direction of one of its dimensions by a plurality of reversing cuts formed by continuous cutting operations, the reversing cuts being oppositely directed and the reversing parts of the cuts 105 being in the same transverse alinement, and also intermittently severing the strips formed by the reversing cuts by a series of separate parallel cuts formed in the sheet in the direction of its other dimension, said 110 parallel cuts terminating in reversing portions of the plurality of reversing cuts.

2. The herein described method of forming a plurality of shingles from a single sheet of material, which consists in severing the sheet by a plurality of zig-zag cuts arranged side by side in the direction of one of its dimensions, but in which the points of the adjacent zig-zag cuts in the same 115 alinement are oppositely directed, and severing the sheet in the direction of its other dimension by parallel cuts connecting the said oppositely directed adjacent points of severance of successive zig-zag cuts.

3. The herein described method of forming a plurality of shingles from a single sheet of material, which consists in severing the sheet by a series of zig-zag cuts in the direction of one of its dimensions, but 125 in which the points of the adjacent zig-zag 130

cuts in the same alinement are oppositely directed, and in which further, the angularity of the points of the successive adjacent zig-zag cuts is different, and severing 5 the sheet in the direction of its other dimension by staggered parallel cuts connecting the said oppositely directed adjacent points of severance of successive zig-zag cuts, whereby individual shingles are formed 10 having points at opposite ends, in which the points at one end are of greatly less angularity than the points at the other end.

4. The herein-described method of forming shingles from a single sheet of material, 15 which consists in severing the material by continuously cutting along the length thereof in the direction of one of its dimensions by a plurality of parallel zig-zag cuts with the points of the adjacent zig-zag cuts oppositely directed in the same alinement and 20 of different angular dimensions, and severing the sheet in the direction of the other of its dimensions by a plurality of staggered parallel cuts, terminating in the points 25 of the zig-zag cuts, whereby shingles are simultaneously formed having three distinct shapes, one double pointed with different angularities for each of its points, and the

other two shingles of general rectangular form and having points at one end only 30 but of different angularities.

5. The herein described method of forming a plurality of shingle structures from a single sheet of material, which consists in severing the sheet of material in the direction of one of its dimensions with a plurality of symmetrical reversing continuous cuts, but in which the narrow or pointed portions of adjacent reversing cuts in the same alinement are oppositely directed, severing the sheet of material in the direction of its other dimension by parallel cuts connecting said oppositely directed adjacent narrow or pointed portions of the reversing cuts and extending to the side edges of the 45 sheet, and also severing the sheet of material in the last mentioned direction and between the adjacent reversing cuts by other series of parallel separate cuts.

In testimony of which invention, I here- 50 unto set my hand.

CALVIN RUSSELL.
